CLAIM

The ornamental design of a bearing frame, as shown in the figures and described.

DESCRIPTION

FIG. 1 is a front perspective view of a bearing frame illustrating the design of the present invention;

FIG. 2 is a front view of the bearing frame of FIG. 1;

FIG. 3 is a right side view of the bearing frame of FIG. 1;

FIG. 4 is a left side view of the bearing frame of FIG. 1;

FIG. 5 is a rear view of the bearing frame of FIG. 1;

FIG. 6 is a bottom view of the bearing frame of FIG. 1; and,

FIG. 7 is a top view of the bearing frame of FIG. 1.

The broken lines depict portions of the bearing frame that form no part of the claimed design.
